UNITED STATES PATENT OFFICE.

JOHN F. FOX, OF BIRMINGHAM, ALABAMA.

RUNNING-GEAR AND DRAW-BAR ATTACHMENT FOR MINE-CARS.

1,077,601.

Specification of Letters Patent.

Patented Nov. 4, 1913.

Application filed March 27, 1913. Serial No. 757,182.

To all whom it may concern:

Be it known that I, JOHN F. FOX, a citizen of the United States of America, residing at Birmingham, in the county of Jefferson and State of Alabama, have invented certain new and useful Improvements in Running-Gear and Draw-Bar Attachments for Mine-Cars, of which the following is a specification.

My invention relates to certain new and useful improvements in running gear and draw bar attachments for cars, and particularly for mine cars where the axles have been directly connected to the car body and not to a truck.

One object of my invention is to attach the journal boxes for both axles to a flexible metal plate which in turn is bolted to the bottom of the car. This plate is made sufficiently rigid to hold the axles in parallelism while it is flexible enough to accommodate itself in the bending or giving of the car body. It has the obvious advantage of mounting the running gear on a part separate from the wooden body so that it may be readily removed and transferred to another car at a small cost. The vibration of the plate between its points of support on the axle boxes relieves the jars from the track irregularities and by giving a spring support to the car increases its life.

A further object of my invention has been to so design the running attachments for the car that I am enabled to apply spring draw bars to the ordinary mine car at a comparatively small expense. The difficulty heretofore in applying a draw bar to a mine car has been that either a long heavy beam has been extended from end to end under the car which raised the car body above the axles, or the axles were bent down under the bar, or the draw bar was at a considerable expense formed of metal and bent down so as to pass under the axles. I avoid these difficulties by providing a central longitudinal brace plate which passes under the axles and has its ends connected to the down turned flanged ends of the plate upon which the journal boxes are mounted. Separate draw bars are mounted at each end of the

car and are held by springs which are fastened to the adjacent ends of the two plates. This gives a light but strong construction which permits the car to be set low and close to the axles and, without sacrificing strength and rigidness, permits the car to be equipped with draw bars at comparatively small expense.

My invention comprises other details of construction and arrangement of parts which are hereinafter more particularly described and claimed and illustrated in their preferred embodiment in the accompanying drawings, in which:

Figure 1 is a side view partly in section and partly in side elevation taken on the line $x-x$ of Fig. 2. Fig. 2 is a bottom view of a mine car equipped with my improvements, one journal box being removed. Fig. 3 is a partial end elevation of the car showing the draw bar in end elevation. Fig. 4 is a view taken on the line $y-y$ of Fig. 2.

Similar reference numerals refer to similar parts throughout the drawings.

The body 1 of the car may be of any suitable construction but that shown is an ordinary wooden body mine car having end bails 2 and a bottom 3. To the underside of the bottom 3 I attach a metal plate 4 having its ends bent down at 5 to form bracing or reinforcing flanges crosswise of the car. This plate 4 is connected by a set of bolts or rivets 6 to the bottom 3 of the car and at each corner is provided with a circular opening 7 and a series of bolt openings 8. Journal boxes 9 are provided with bosses 10 which fit into the sockets or openings 7 in the plate 4 and the boxes are rigidly connected to the plate by bolts 11 which pass through the journal box and through the plate. Any suitable type of axles 12 are mounted in these boxes and have wheels 13 mounted at their outer ends. Along the longitudinal center line of the car and below the axles 12 is provided a narrow brace plate 14, the ends of which are bent over so as to overlap and fit snugly against the ends 5 of the plate 4. At its center this brace plate 14 is rigidly connected to the top plate 4 by

means of an angle plate 15 connected by rivets 16 to the center of plate 15 and having its ends inclined upwardly at an angle and riveted to the under face of the plate 4.

- 5 The manner of connecting the draw bars for each end of the car is the same and only one construction will be described. A draw bar 17 of any suitable type is supported at its outer end in a clip 18 bolted to the under-
 10 side of the bail 2. The inner reduced end or shank 22 of the draw bar is riveted or otherwise fastened to a washer 19 which serves as an inner seat for a coil spring 20, which at its outer end bears against a slide
 15 plate 21 having a central opening through which the shank of the draw bar passes. The slide plate 21 at each end is rigidly connected by bolts 23 to the overlapping ends of the plates 4 and 14, the draw bar being
 20 free to move longitudinally against the action of the coil spring 20. It will be noted that the manner in which the plates 4 and 14 are overlapped at their ends and braced in
 25 their centers will give an exceedingly strong and rigid structure to which the draw bars are connected. It will also be noted that all of the running gear, as well as the draw bar connection, can be readily disconnected from a car. The plate 4, while deriving much
 30 strength from the bottom of the car, will be always sufficiently rigid to hold the axles in true parallelism and yet be flexible enough to accommodate itself to the bending or flex-
 35 ing of the car body.
- 6 It is not essential that the ends of the plates 4 and 14 be overlapped for other means may be devised for connecting the spring holding means for each draw bar to the adjacent ends of the said plates.

- 40 What I claim as new and desire to secure by Letters Patent, is:—

1. In a running gear for cars, the combination with the bottom of a car, of a metal plate attached thereto, journal boxes for the axles of the car which are connected to the corners of said plate which holds the axles in parallelism, and means to reinforce said plate transversely of the car while leaving its body free to flex lengthwise of the car, as and for the purposes described.

2. In a running gear for mine cars, the combination with the bottom of a car, of a flexible metal plate attached to the underside thereof, journal boxes for the axles of the car which are connected near the ends of said plate which holds the axles in parallelism, the axles being spaced from said plate, and means to reinforce said plate transversely of the car adjacent to the axles while leaving the body of the plate free to flex and vibrate, as and for the purposes described.

3. In a running gear for mine cars, the combination with the car body, of a metal

plate detachably connected to the underside 65 of the car body, means to reinforce the plate transversely, journal boxes for the car axles which are attached to said plate, a longitudinal reinforcing plate which extends under the axles and is connected at 70 its ends to said first mentioned plate, substantially as described.

4. A running gear for mine cars comprising in combination a main metal plate attached to the underside of the bottom of the 75 car and having its ends bent down, journal boxes for the car axles which are connected to said plate, and a longitudinal reinforcing plate which at its center is braced to the main plate and has its ends upturned and 80 connected to the downturned ends of the metal plate, substantially as described.

5. In a mine car, a main metal plate connected to the bottom of the car, a reinforcing plate disposed longitudinally of the car 85 and spaced from said main plate, braces to connect the main and reinforcing plates near the center of the latter, and a draw bar at each end of the car which is connected to the adjacent ends of the main and reinforcing 90 plates, substantially as described.

6. In a mine car, a main plate connected to the underside of the bottom of the car, journal boxes for the wheel axles which are connected to said plate, a reinforcing plate 95 narrow relatively to the main plate which is disposed lengthwise of the car and adapted to pass under the axles, means to connect the main and reinforcing plates at their centers, spring frames, one of which is connected to the adjacent ends of the main and reinforcing plates at each end of the car, a draw bar slidably mounted at each end of the car, and a spring mounted in each frame and engaging the inner end of a draw 105 bar to hold the latter retracted, substantially as described.

7. In a mine car, a metal plate having substantially the width of the car which is connected to the underside of the bottom of 110 the car and has its two ends spaced from the ends of the car and bent down, a narrow reinforcing plate having its ends bent up and adapted to lap the down turned ends of the wide plate, means to brace the two 115 plates together near their centers, and means to connect a draw bar to said plates at each end of the car, each of said draw bar connecting means comprising a pair of bolts which are bolted to the overlapping ends of 120 the two plates, a cross piece to which said bolts are connected at their outer ends, each draw bar having its inner ends adapted to project inwardly of its respective cross piece, and a spring interposed between each 125 cross piece and the inner end of its respective draw bar, substantially as described.

8. In a running gear for mine cars, the

combination with the bottom of a car, of a flexible metal plate which, near its ends, is connected to the underside of the bottom of the car and has its middle portion left free
5 of rigid connection to said bottom, means to attach journal boxes of both car axles to said plate near its ends, the axles being spaced from the plate, and means to reinforce the

plate transversely adjacent to each axle, substantially as described. 10

In testimony whereof I affix my signature in presence of two witnesses.
